UNITED STATES PATENT OFFICE

2,469,453

MACHINE FOR OPERATING ON SHOES

George H. Collins, Lynn, Mass., assignor to United
Shoe Machinery Corporation, Flemington, N. J.,
a corporation of New Jersey

Application February 11, 1948, Serial No. 7,611

18 Claims. (Cl. 12—34)

1

This invention relates to machines for operating on work pieces, and more particularly to machines for leveling the bottoms of shoes. While the invention is herein illustrated with reference to that type of machine having a shoe support arranged for movements in directions lengthwise of a shoe thereon to carry the shoe below a leveling roll which thus acts progressively along the shoe bottom, and in which the leveling roll is arranged for tipping movements about an axis extending lengthwise of the shoe on the support to impart the desired bottom character to the shoe, it will be understood that the invention is not limited in use, to machines of the type herein illustrated nor to machines for leveling the bottoms of shoes.

An object of the invention is to provide means for controlling the movements of a work support relatively to a tool and the movements of the tool relatively to the support by the use of a single manually-operated member.

As a further object the invention has in view, in a machine in which the work support and the tool are each moved by power-operated means, the provision of a control member operating in response to its movement along one path to control the power-operated means for moving the work support and in response to its movement along a path angularly related to the first path to control the power-operated means for moving the tool relatively to the work support.

More specifically, it is an object of the invention to provide an improved leveling machine in which the movements of a work support in directions lengthwise of a shoe thereon to carry the shoe past a leveling roll, and the tipping movements of the leveling roll relatively to the work support are both controlled by means of a single manually-operated member.

For the purposes in view and in accordance with a feature of the invention, the work support is moved by a fluid pressure-operated member and the tool or leveling roll is moved relatively to the work support by a second fluid pressure-operated member, the fluid pressure-operated members being controlled by valves which are in turn controlled by a single manually-operated member. The speed, direction, and extent of movements of the work support and of the tool are controlled in accordance with the speed, direction, and extent of movements of the control member.

In accordance with a still further feature of the invention, the manually-operated member by which the movements of the work support and of the tool or leveling roll are controlled is capable

2

of moving forwardly or rearwardly at any point in its movement laterally of the machine and is capable of moving laterally at any point in its movement forwardly or rearwardly of the machine.

The above and other features of the invention, including various novel details of construction and combinations of parts will now be more particularly described by reference to the accompanying drawings and pointed out in the claims.

In the drawings,

Fig. 1 is a view in right hand side elevation of a machine in which the invention is embodied, parts of the structure being broken away and other parts being shown in section;

Fig. 2 is an enlarged side elevation of the hand control member and associated parts for controlling the movements of the jack and the tipping of the roll;

Fig. 3 is a front elevation of the hand control member of Fig. 2;

Fig. 4 is an end elevation, partly in section, of the hand control member of Fig. 2;

Fig. 5 is a plan view, partly in section, of a portion of the mechanism shown in Fig. 2; and

Fig. 6 is a front elevation of the lower portion of the hand control member showing the connections to the jack-moving mechanism.

The invention is illustrated herein as embodied in a machine of the type shown in Letters Patent of the United States No. 2,230,244 granted February 4, 1941 on an application filed in the names of Fred V. Hart and John J. Austin. The machine includes a main frame 10 within which is pivotally mounted a shoe support or jack 12 on a shaft 14. The jack includes a toe post 16 fast on the shaft 14 and a heel post 18 loosely mounted on the shaft 14. The toe and heel posts are locked together by mechanism controlled by an arm 20 after the shoe has been placed on the jack and after the heel post has been adjusted in position relatively to the toe post in accordance with the size of the shoe to be operated upon, as described more fully in the patent referred to above.

The jack is moved by mechanism to be described about the axis of the shaft 14 to carry the shoe rearwardly and forwardly beneath a leveling roll 22 which is arranged to be held against the bottom of the shoe under heavy pressure as will be explained. This roll is mounted for turning movement on a rod 24 in a holder 26 pivotally connected at 28 to a carrier 30. This carrier is mounted for tipping movements laterally of the machine about the axis of a forwardly and rear-

wardly extending shaft 32 supported in bearings at the top of the frame 10. The holder 26 has a rearwardly extending arm 34 connected by a short link 36 to the rearwardly extending arm 38 of a bell crank lever 40 fulcrumed at 42 to the carrier 30. The bell crank lever 40 has a pair of downwardly extending arms 44 carrying trunnions 46 extending into a circumferential groove 47 formed in a bushing 48 that is slidably mounted on the shaft 32. Pivotally mounted on a laterally extending shaft 50 supported by suitable bearings in the frame 10 is an upwardly extending arm 52 the upper portion of which is forked to straddle the bushing 48, the arms of the forked portion carrying trunnions 54 extending into a circumferential groove 56 formed in the bushing 48. Mounted on the shaft 50 is a downwardly extending yoke member 58 and connected to this member by a threaded rod 60 is a yoke-shaped member 62 between the arms of which at their lower ends is pivoted a lever 64. This lever has oppositely extending arms of equal lengths to the ends of which are pivotally connected abutments 66, 68 for heavy expansion springs 70, 72. The upper end of the spring 72 bears against an abutment 74 pivotally connected at 76 to the frame 10. The upper end of the spring 70 engages an abutment 78 pivotally connected to an arm 80 integral with the arm 52. The springs 70, 72 act to move the arm 80 and with it the arm 52 in a clockwise direction during the leveling operation thereby to move the bushing 48 rearwardly along the shaft 32 thus rocking the bell crank lever 40 in a counterclockwise direction and forcing the leveling roll 22 downwardly against the shoe bottom.

At the beginning of the leveling operation the roll 22 is lifted against the action of the springs 70, 72 to prevent stubbing the toe end of the shoe during its movement beneath the leveling roll. For this purpose there is formed integral with the arm 52 a third arm 82 connected by an adjustable link 84 to one end of a lever 86 pivoted intermediate its ends to a bracket 88 secured to the frame 10. The lever 86 has its opposite end portion forked to straddle a plunger 90, the arms of the forked portion carrying trunnions which extend into a peripheral groove formed in the upper end of the plunger. This plunger is connected to a piston movable in a cylinder 92 so that upon admission of fluid under pressure into the lower end of the cylinder the lever 86 is rocked in a counterclockwise direction thereby moving the arm 52 in a counterclockwise direction and moving the bushing 48 forwardly along the shaft 32 to lift the leveling roll against the action of the springs 70, 72.

Fluid under pressure is supplied by a pump 94 mounted in a reservoir 96 in the bottom of the frame 10. Fluid from the pump is delivered through a pressure-regulating valve 98 which may be constructed as shown in the Hart et al. patent, referred to above, and this valve is arranged so that when the jack is in its forward position, as shown in Fig. 1, fluid is delivered directly from the valve back to the reservoir. However, the valve is operated upon straightening a toggle mechanism 100 to deliver fluid under high pressure to mechanism by which the roll 22 is tipped and by which the jack 16 is moved forwardly and rearwardly in the leveling operation. This toggle is arranged to be straightened by a rod 102 which is moved forwardly of the machine by a spring 104 upon the initial rearward movement of the jack, as fully described in the Hart et al. patent. Fluid under pressure now flows

5 into the lower portion of the cylinder 92 lifting the leveling roll and upon further rearward movement of the jack, flow of pressure fluid to the cylinder is cut off substantially at the time that the toe end of the shoe moves beneath the leveling roll, as shown in the Hart et al. patent, whereupon the roll is forced downwardly into engagement with the shoe bottom by the springs 70, 72.

10 For tipping the leveling roll 22 during the leveling operation, the carrier 30 has extending laterally from it an arm 106 to which is pivoted an adjustable link 108 the lower end of which is pivoted to a lever 110 keyed to a shaft 112. This shaft is operatively connected for rocking movements to a fluid pressure motor 114, as shown in detail in the Hart et al. patent. Pressure fluid is conducted into the upper and lower ends of the motor through pipes 116 and 118 respectively, the direction of tipping movement of the leveling roll depending upon whether the pressure fluid is admitted into the upper or lower end of the motor. For controlling the admission of pressure fluid into the motor 114 a valve 120 is provided, this valve being connected by a pipe 122 to the pressure-regulating valve 98. The pipes 116 and 118 are connected to the upper and lower ends of the valve 120 respectively whereas the pipe 122 is connected to a mid portion of the valve. This valve includes a valve element, as shown in the Hart et al. patent, provided with an upwardly extending rod 124 arranged when the rod is moved upwardly to permit fluid to flow from the pipe 122 through the pipe 116 and when the rod 124 is moved downwardly to permit the fluid to flow through the pipe 118. With the rod in the mid-position shown, the valve prevents flow of fluid through either of pipes 116, 118.

15 For operating the valve 120 a bell crank lever 126 is fulcrumed at 128 in the machine frame, one arm of this lever being connected by a pair of links 130 to a lever 132 one end of which is pivotally connected at 134 to the rod 124, the other end of the lever 132 being connected to the upper end of a link 136 the lower end of which is pivoted at 138 to the lever 110. When the bell crank lever 126 is moved in a counterclockwise direction, as viewed in Fig. 1, the lever 132 moves downwardly about its connection to the link 136 thereby to admit pressure fluid into the lower end of the motor 114. The shaft 112 is now turned in a counterclockwise direction to tip the leveling roll and at the same time to move the link 136 downwardly whereupon the lever 132 pivots about its connection with the link 130 to lift the rod 124 moving the valve element in the valve 120 back to mid-position. Thus there is provided a follow-up movement so that the speed and extent of movement of the leveling roll depends upon the speed and extent of movement of the valve element by the bell crank 126. It will also be understood that the direction of tipping movements depends upon the direction in which the bell crank 126 is moved. The mechanism for moving the bell crank to control the tipping of the leveling roll will be described later.

20 For imparting swinging movements to the jack 12 an arm 140 surrounds the shaft 14 and is secured to the toe post 16 of the jack. This arm is provided with segmental teeth 142 on its rearward portion and is connected by gearing (not shown) with the rack of a fluid pressure motor 144 which is similar in construction to the motor 114. To the upper and lower ends of the motor 144 are connected pipes 146, 148 respectively, leading to the opposite ends of a valve 150 (Fig.

2) to the mid portion of which is connected a pipe 152 leading from the pressure-regulating valve 98. The valve 150 includes an upwardly extending rod 154 arranged upon upward movement to direct fluid under pressure through the pipe 146 into the upper end of the fluid pressure motor 144 and when the rod 154 is moved downwardly pressure fluid flows through the pipe 148 into the lower end of the motor 144, thereby to control the direction of swinging movement of the jack.

The rod 154 has a head 156 to which is pivoted at 158 one end of a lever 160 the other end of which is connected by downwardly extending links 162 to a rack 164. To the lever 160 are pivoted downwardly extending links 166 connected to an arm 168 of a bell crank lever 170 pivoted at 172 to the frame of the machine. The bell crank lever 170 includes a downwardly and forwardly extending arm 174 to the lower end of which is pivoted a link 176 connected to a lever 178 pivotally carried by the frame. Upon movement of the lever 178 in a clockwise direction, as viewed in Fig. 2, the bell crank lever 170 is moved in a counterclockwise direction moving the forward end of the lever 160 downwardly about its pivotal connection with the link 162 thereby moving the rod 154 of the valve 150 downwardly and admitting pressure fluid to the lower end of the motor 144 (Fig. 1) whereupon the jack is moved rearwardly to carry the shoe beneath the leveling roll. As shown in the Hart et al. patent, this movement of the jack causes the rack 164 to be moved downwardly whereupon the lever 160 pivots in a clockwise direction about its connection with the links 166 to return the rod 154 of the valve to its mid-position. Thus it will be understood that the speed, direction and extent of movement of the jack depend upon the speed, direction and extent of movement of the lever 178.

For controlling the valves 120, 150, a hand lever 182 (Figs. 2 and 3) is fulcrumed upon a pin 184 carried by the parallel walls of a U-shaped arm 186. This arm is in turn fulcrumed at its lower end upon a shaft 188 carried by a boss 190 extending forwardly from the frame 10. For limiting movement of the lever 182 within the arm 186, the lever near its upper end carries a bolt 192 which moves in slots 194 formed in the parallel walls of the arm 186. The lower end of the lever 182 is forked at 196 to embrace the head 198 of a vertically extending pin 200 journaled in an arm 202 which is in turn secured to the lower end of a vertical shaft 204 journaled in the frame 10. The head 198 of the pin 200 is provided with spherical surfaces engageable with the inner surfaces of the forked end of the lever 182 to permit freedom of movement between the lever and the pin upon movement of the lever about its fulcrum 184 or upon movement of the arm 186 about the shaft 188.

To the upper end of the shaft 204 (Figs. 4 and 5) is secured an arm 206 which is in turn connected to one end of an extensible link 208 which passes through a sleeve 210 held by a bracket 212 secured to the frame of the machine. The other end of the link 208 is connected to the lower end of a depending arm 214 (Figs. 2 and 5) of the bell crank lever 126. Thus it will be understood that upon movement of the lever 182 laterally of the machine about the pivot 184 the bell crank lever 126 is moved about the pivot 128 to operate the valve 120 thereby to control the tipping movements of the leveling roll. The direction, extent and speed of tipping movement

of the roll is controlled in accordance with the direction, extent and speed of movement of the lever 182.

Provision is made for insuring that the leveling roll will be moved to a substantially horizontal position when the lever 182 is released by the operator so that the roll will be properly positioned in its angular relation to the shoe bottom at the beginning of the leveling operation. For this purpose springs 216, 218 (Fig. 5) surround the link 208 within the sleeve 210 and at their adjacent ends engage shoulders formed within the central portion of the sleeve. The outer ends of the springs engage collars 220, 222 respectively, near the outer ends of the link 208. These collars carry pins 224 which extend through slots 226 in the sleeve 210 to prevent turning of the collars with respect to the link 208 when the operator releases the lever 182. At the end of the leveling operation the springs 216, 218 will cause the link 208 to assume a mid-position with respect to the sleeve 210 in which the lever 182 is in a mid-position with respect to its movement laterally of the machine.

The lower end of the arm 186 in which the lever 182 is pivoted includes a forwardly extending projection 226 (Fig. 2) connected to the upper end of a downwardly extending link 228, the lower end of which is pivoted to an arm 230 pinned to one end of a shaft 232 extending laterally of the machine. This shaft is carried by bearings 234 in the frame 10 at opposite sides of the machine. Pinned to the other end of the shaft 232 (Fig. 6) is a forwardly extending arm 236 connected to an upwardly extending link 238 the upper end of which is connected to an arm 240 extending forwardly from the lever 178. It will be understood that when the arm 186 is moved about the shaft 188 by movement of the lever 182 forwardly or rearwardly of the machine the lever 178 is caused to partake of a similar movement thereby controlling, through the connections heretofore described, the valve 150 by which the swinging movements of the jack are controlled.

45 The direction, speed and extent of movement of the jack will depend upon the direction, speed and extent of movement of the lever 182 with the arm 186 about the axis of the shaft 188.

Mechanism is provided for lifting the leveling roll at any time during the leveling operation against the action of the springs 10, 72. For this purpose a treadle 242 (Fig. 1) is pivoted at 244 to the frame of the machine and is urged upwardly by a spring 246 to a position determined by a stop screw 248. Connected to the treadle 242 is an upwardly extending extensible link 250 having a slotted upper end 252. Extending through the slot is a pin 254 carried by an arm 256 secured to a shaft 258. This shaft carries an arm 260 pivoted at its upper end to the forward end of the rod 102. The forward movement of the rod 102 under the action of the spring 104 during the leveling operation is limited by engagement of the pin 254 with the link 250 at the upper end of the slot 252. If the treadle 242 is depressed during the leveling operation the rod 102 is moved rearwardly causing the admission of pressure fluid into the cylinder 92 thereby lifting the leveling roll, as described in the Hart et al. patent.

70 It is desirable to limit the forward movement of the jack by the lever 182 during the leveling operation so that the toe end of the shoe will not be carried forwardly of the leveling roll. For this purpose a latch 262 (Fig. 2) is pivoted at 264 to an arm 266 depending from the lever 178. This

latch carries a pin 268 which rides in the slot 270 in the upper end of a link 272, the lower end of which is pivoted at 274 to a treadle 276. This treadle is pivoted at 278 to the frame of the machine and is urged upwardly by a spring 280. The rearward end of the latch 262 is recessed to form a shoulder 282 which engages a pin 284 in the frame of the machine during the leveling operation to limit the forward movement of the jack. When the lever 182 is moved rearwardly at the beginning of the leveling operation the latch 262 is carried forwardly and urged upwardly by the spring 280 connected to the treadle 276. Upon subsequent forward movement of the lever 182 the shoulder 282 contacts the pin 284 at the proper time to limit the forward movement of the lever 182. The extent of upward movement of the latch 262 is limited by a stop 286 carried by the arm 266. It will be understood that as the jack is moved rearwardly by movement of the lever 182 the latch 262 will be carried out of engagement with the pin 284 but the stop 286 is so located as to hold the latch 262 in the proper position so that the shoulder 282 will move into engagement with the pin 284 to limit the forward movement of the jack. At the conclusion of the leveling operation the treadle 276 is depressed to withdraw the latch 262 from engagement with the pin 284 so that the jack may be moved back into its loading position as shown in Fig. 1.

From the above it will be seen that I have provided a leveling machine in which a single hand lever 182 is employed to effect the tipping movements of the leveling roll and the movements of the jack to carry the shoe forwardly and rearwardly beneath the leveling roll in the leveling operation. The direction, speed and extent of movement of the jack and of the tipping movements of the leveling roll are controlled in accordance with the direction, speed and extent of movements of the lever 182.

Having thus described the invention, what I claim as new and desire to secure by Letters Patent of the United States is:

1. In a machine for operating on work pieces, a work support, a tool, means mounting said work support for movements relatively to said tool, means mounting said tool for movements relatively to said work support, and a single manually-operated member for selectively controlling the movements of said work support and said tool.

2. In a machine for operating on work pieces, a work support, a tool, means mounting said work support for movements relatively to said tool, means mounting said tool for movements relatively to said work support, power-operated means for thus moving said work support and said tool, and a single manually-operated member in control of said power-operated means for selectively moving said work support and said tool.

3. In a machine for operating on work pieces, a work support, a tool, means mounting said work support for movement relatively to said tool, means mounting said tool for movement relatively to said work support, power-operated means for thus moving said work support and said tool, a control member movable by the operator along two angularly related paths, means operated in response to movement of the control member along one path for controlling said power-operated means to move the work support, and means operated in response to movement of the control member along another path for controlling said power-operated means to move the tool.

4. In a machine for operating on work pieces, a

work support, a tool, power-operated means for moving said work support relatively to said tool, power-operated means for moving said tool relatively to said work support, a control member movable along two angularly related paths, means operated by said control member in response to its movement along one path for controlling the first of said power-operated means, and means operated by said control member in response to its movement along the other path for controlling the second of said power-operated means.

5. In a machine for operating on work pieces, a work support, a tool, means mounting said work support for movement relatively to said tool, means mounting said tool for movement relatively to said work support, separate power-operated means for thus moving said work support and said tool, and means for controlling said power-operated means including a member movable by the operator forwardly and rearwardly of the machine for starting one of said power-operated means in operation and being movable laterally of the machine to start the other of said power-operated means in operation.

6. In a machine for operating on work pieces, a work support, a tool, means mounting said work support for movement relatively to said tool, means mounting said tool for movement relatively to said work support, separate power-operated means for thus moving said work support and said tool, means for controlling said power-operated means including a member movable by the operator forwardly and rearwardly of the machine for starting one of said power-operated means in operation and being movable laterally of the machine to start the other of said power-operated means in operation, and means mounting said member for movement forwardly or rearwardly of the machine at any point in its movement laterally of the machine and for movement laterally of the machine at any point in its movement forwardly or rearwardly of the machine.

7. In a machine for operating on work pieces, a work support, a tool, power-operated means for moving said work support relatively to said tool, power-operated means for moving said tool relatively to said work support, and means for controlling said power-operated means including a member movable by the operator along one path for starting one of said power-operated means in operation to move the work support in accordance with the direction and extent of movement of the control member, said member being movable along another path to start the other of said power-operated means in operation to move the tool in accordance with the direction and extent of movement of the control member.

8. In a machine for operating on work pieces, a work support, a tool, power-operated means for moving said work support relatively to said tool, power-operated means for moving said tool relatively to said work support, and means for controlling said power-operated means including a member movable by the operator forwardly and rearwardly of the machine for starting one of said power-operated means in operation to move the work support in accordance with the direction and extent of each rearward and forward movement of the control member, said member being movable laterally of the machine to start the other one of said power-operated means in operation to move the tool in accordance with the direction and extent of each lateral movement of the control member.

9. In a machine for operating on work pieces, a

work support, a tool, power-operated means for moving said work support relatively to said tool, power-operated means for moving said tool relatively to said work support, means for controlling said power-operated means including a member movable by the operator forwardly and rearwardly of the machine for starting one of said power-operated means in operation to move the work support in accordance with the direction and extent of forward or rearward movement of the control member, said member being movable laterally of the machine to start the other one of said power-operated means in operation to move the tool in accordance with the direction and extent of lateral movement of the control member, and means mounting said control member for movement forwardly or rearwardly of the machine at any point in its movement laterally of the machine and for movement laterally of the machine at any point in its movement forwardly or rearwardly of the machine.

10. In a machine for operating on work pieces, a work support, a tool, means for moving said work support relatively to said tool to move the work progressively past said tool, means for moving said tool to vary its position relatively to said work support, a single operating member movable along two paths, means operated by said member in response to its movement along one path for controlling the first means to move the work support a distance depending upon the extent of movement of said member, and means operated by said member in response to its movement along the other path to control the second named means to vary the position of the tool relatively to the work support.

11. In a leveling machine, a leveling roll, a shoe support, means for moving the shoe support in directions lengthwise of a shoe thereon to cause the leveling roll to operate progressively along the shoe bottom, means for tipping the leveling roll laterally of the shoe support, and a single manually-operated member for controlling both of said means.

12. In a leveling machine, a leveling tool, a shoe support, a control member movable forwardly and rearwardly of the machine and laterally thereof, means operated in response to movement of the control member forwardly and rearwardly of the machine for causing similar movement of said shoe support, and means operated in response to movement of the control member laterally of the machine for causing said leveling tool to tip relatively to a shoe on the support.

13. In a leveling machine, a leveling tool, a shoe support mounted for movements in directions lengthwise of a shoe thereon, power-operated means for thus moving said shoe support, power-operated means for tipping the leveling tool relatively to a shoe on the support, a control member, and means operated by said control member in response to its movement along one path for operating the first named power-operated means and movable along another path for operating the second named power-operated means.

14. In a leveling machine, a leveling tool, a shoe support movable in directions lengthwise of a shoe thereon, means for thus moving said shoe support, means for tipping said leveling tool, a single operating member movable along two paths, means operated by said member in response to its movement along one path for controlling the first means to move the work support a distance depending upon the extent of move-

ment of said member, and means operated by said member in response to its movement along the other path to control the second named means to tip the leveling tool in accordance with the extent of movement of said member along said other path.

15. In a leveling machine, a leveling tool, a shoe support mounted for movements in directions lengthwise of a shoe thereon, separate power-operated means for thus moving said work support and for tipping said leveling tool relatively thereto, means for controlling said power-operated means including a member movable by the operator forwardly and rearwardly of the machine for starting one of said power-operated means in operation and being movable laterally of the machine to start the other one of said power-operated means in operation, and means mounting said member for movement forwardly or rearwardly of the machine at any point in its movement laterally of the machine and for movement laterally of the machine at any point in its movement forwardly or rearwardly of the machine.

16. In a leveling machine, a leveling roll, a shoe support mounted for swinging movements in directions lengthwise of a shoe thereon to cause the leveling roll to operate progressively along the shoe bottom, fluid-pressure means for swinging said shoe support, fluid-pressure means for tipping the leveling roll laterally of the shoe support, and a single manually-operated member for controlling both of said fluid-pressure means.

17. In a leveling machine, a leveling roll, a shoe support mounted for swinging movements in directions lengthwise of a shoe thereon to cause the leveling roll to operate progressively along the shoe bottom, fluid-pressure means for swinging said shoe support, fluid-pressure means for tipping the leveling roll laterally of the shoe support, a control member movable along different paths, means operated by the control member in response to its movement along one path for controlling the first named fluid-pressure means, and means operated by the control member in response to its movement along another path for controlling the second named fluid-pressure means.

18. In a leveling machine, a leveling roll, a shoe support mounted for swinging movements in directions lengthwise of a shoe thereon to cause the leveling roll to operate progressively along the shoe bottom, fluid-pressure means for swinging said shoe support, fluid-pressure means for tipping the leveling roll laterally of the shoe support, a control member movable forwardly and rearwardly of the machine and laterally thereof, means operated by said control member in response to its movement forwardly and rearwardly of the machine for controlling the first named fluid-pressure means, and means operated by said control member in response to its movement laterally of the machine for controlling the second named fluid-pressure means.

65 GEORGE H. COLLINS.
